PANEL FOR HOUSEHOLD APPLIANCES

Nelson R. Peet, Jr., Syracuse, N. Y.

Application April 15, 1949, Serial No. 1,994

Term of patent 14 years

(Cl. D49—1)

To all whom it may concern:

Be it known that I, Nelson R. Peet, Jr., a citizen of the United States of America, residing at Syracuse, in the county of Onondaga and State of New York, have invented a new, original, and ornamental Design for a Panel for Household Appliances, of which the following is a specification, reference being had to the accompanying drawings, forming part thereof, in which:

Figure 1 is a perspective view on a reduced scale of a panel for household appliances, showing my new design;

Figure 2 is a front elevation of the panel;

Figure 3 is a longitudinal section of the panel taken on the line 3—3 of Figure 2;

Figure 4 is a vertical section taken on the line 4—4 of Figure 2; and

Figure 5 is a vertical section taken on the line 5—5 of Figure 2.

I claim:

The ornamental design for a panel for household appliances, substantially as shown.
